UNITED STATES PATENT OFFICE.

CHARLES H. SANFORD, OF DADEVILLE, ALABAMA.

FERTILIZER-DISTRIBUTER.

SPECIFICATION forming part of Letters Patent No. 699,247, dated May 6, 1902.

Application filed October 24, 1901. Serial No. 79,858. (No model.)

To all whom it may concern:

Be it known that I, CHARLES H. SANFORD, a citizen of the United States, residing at Dadeville, in the county of Tallapoosa and State of Alabama, have invented certain new and useful Improvements in Fertilizer-Distributors; and I do declare the following to be a full, clear, and exact description of the invention, such as will enable others skilled in the art to which it appertains to make and use the same.

The invention relates to fertilizer-distributors.

The object of the invention is to provide a machine of this character which shall be simple of construction, durable in use, comparatively inexpensive of production, efficient in operation, capable of adjustment for regulating the amount of discharge of the fertilizing material, and easily attached to the stock of a plow or other tilling implement.

With these and other objects in view the invention consists of certain novel features of construction, combination, and arrangement of parts, which will be hereinafter more fully described, and particularly pointed out in the appended claim.

In the accompanying drawings, Figure 1 is a side elevation showing the invention attached to an ordinary plow-stock. Fig. 2 is a longitudinal sectional view through the hopper and vibrating shoe, showing in full lines one adjustment of the shoe and in dotted lines another adjustment of the shoe; and Fig. 3 is a detail perspective view of the shoe.

Referring to the drawings, 1 denotes a plow-stock, and 2 a hopper, secured thereto in any suitable manner. The forward wall of the hopper may be provided at its lower end with a discharge-opening 3. 4 denotes a vibrating shoe, which is provided with side pieces 5, a rear end piece 6, and has a trough-shaped bottom 7. This shoe is hung near its forward end by pivoted links 8 to the sides of the hopper and is connected at its rear end to the rear side of the hopper by a spring 9. This spring has its lower end preferably pivoted to a staple 10, secured in the rear end of the shoe, and has its upper end vertically and ad-

justably connected to the side of the hopper, 50 preferably by forming the spring with a slot 11, through which extends a set-screw 12. As shown in full lines in Fig. 2 the shoe is so adjusted as to discharge but its minimum amount of fertilizing material and as shown 55 in dotted lines it is adjusted to discharge its maximum amount of fertilizing material. In either adjustment the spring is held securely by the set-screw.

13 denotes an arm secured to the side of the hopper and curved under the shoe and provided with a tappet device, which consists of a disk 14, provided with pins 15, which are adapted to strike an inclined lug 16, secured to the under side of the shoe in the path of 60 movement of said pins and force said lug forwardly. The instant the pin moves from contact with said lug the spring suddenly retracts the shoe rearwardly, and thus discharges the fertilizing material. It will thus 65 be observed that the spring performs two functions—to wit, first, that of returning the shoe to its normal position, which act withdraws the shoe from under the fertilizing material, which has been moved from under the 70 hopper by the pin engaging the inclined lug and allows the fertilizing material to fall to the ground, and, secondly, it serves as a means for supporting in adjusted position 75 the rear end of the shoe to regulate the discharge of the fertilizing material from said hopper.

From the foregoing description, taken in connection with the accompanying drawings, the construction, mode of operation, and advantages of my invention will be readily understood without requiring a more extended explanation.

Various changes in the form, proportion, and details of construction may be made 80 within the scope of the invention without departing from the spirit or sacrificing any of the advantages thereof.

Having thus described my invention, what I claim, and desire to secure by Letters Patent, is—

In a fertilizer-distributer, the combination with the hopper, a shoe having a lug formed

integral therewith, links pivoted to said hopper and said shoe, a tappet device for engaging the lug and moving the shoe in one direction, and a spring for supporting one end of 5 the shoe for returning it to its normal position after having been moved by the tappet device, substantially as set forth.

In testimony whereof I have hereunto set my hand in presence of two subscribing witnesses.

CHAS. H. SANFORD.
